(74) Attorney, Agent, or Firm — Birch, Stewart, Kolasch & Birch, LLP

(73) Assignee: **LG ELECTRONICS INC.**, Seoul (KR)

(57) **CLAIM**

(**) Term: **15 Years**

The ornamental design for an air filter for air purifier with humidifier, as shown and described.

(21) Appl. No.: **35/501,216**

(22) Filed: **Feb. 5, 2016**

DESCRIPTION

(80) **Hague Agreement Data**

Int. Filing Date: **Feb. 5, 2016**

1. Air filter for air purifier with humidifier

Int. Reg. No.: **DM/091386**

1.1 is a perspective view of an air filter for air purifier with humidifier showing our new design;

Int. Reg. Date: **Feb. 5, 2016**

1.2 is a front elevation view thereof;

Int. Reg. Pub. Date: **Jul. 15, 2016**

1.3 is a rear elevation view thereof;

(51) **LOC (11) Cl.** 23-04

1.4 is a left-side elevation view thereof;

(52) **U.S. Cl.**

1.5 is a right-side elevation view thereof;

USPC **D23/364**

1.6 is a top plan view thereof;

(58) **Field of Classification Search**

1.7 is a bottom plan view thereof; and

USPC D23/355, 356, 359, 364, 370, 386

1.8 is a perspective view thereof showing the combined air purifier with humidifier in a use condition.

CPC B01D 46/00; B01D 46/0002; A61L 9/00

The broken line showing in 1.8 is for the purpose of illustrating environment of the air filter for air purifier with humidifier and forms no part of the claimed design.

See application file for complete search history.
